CHARGER FOR BATTERY PACKS

Melvin H. Neuhardt, Baltimore, and Marshall B. Johnson, Bel Air, Md., assignors to The Black and Decker Manufacturing Company, Towson, Md., a corporation of Maryland

Filed Mar. 5, 1962, Ser. No. 69,084

Term of patent 14 years

(Cl. D26—15)

FIG. 1

FIG. 2

FIG. 3

FIG. 4

FIG. 5

FIGURE 1 is a perspective view of a charger for a battery pack, showing our new design.

FIGURE 2 is a rear elevational view;

FIGURE 3 is a front elevational view as viewed from the opposite side of the charger;

FIGURE 4 is a top plan view; and

FIGURE 5 is a side elevational view, the opposite side being substantially the same as the side shown.

We claim:

The ornamental design for a charger for battery packs, as shown and described.
